UNITED STATES PATENT OFFICE.

WILHELM C. A. SIEVERTS, OF QUINCY, MASSACHUSETTS, ASSIGNOR TO LEWIS C. MARSHALL, OF EAST WALPOLE, MASSACHUSETTS.

PRIMING DEVICE FOR EXPLOSION-MOTORS.

1,323,651.

Specification of Letters Patent.

Patented Dec. 2, 1919.

Application filed December 24, 1917. Serial No. 208,536.

To all whom it may concern:

Be it known that I, WILHELM C. A. SIEVERTS, citizen of the United States of America, and resident of Quincy, in the county of 5 Norfolk and State of Massachusetts, have invented new and useful Improvements in Priming Devices for Explosion-Motors, of which the following is a specification.

This invention relates to priming devices 10 for explosion motors of the type adapted to provide an enriched explosive mixture in the cylinder of the motor at the time of starting, so that a low temperature in the carbureter or other chambers of the motor will 15 not prevent the initial explosions, and which shall also be adapted for other related uses.

I am aware of priming devices of the prior art more or less assisting the operation of injecting into the cylinders or intake 20 manifold of an explosion engine gasolene from the motor supply in order to enrich the contents of the explosion chambers before starting. So far as I am aware, such devices involve disadvantages such as necessitating manual labor on the part of the 25 person starting the motor at the moment of starting, when his attention should be directed to other matters, (especially when the engine is the power plant of an automobile); or causing waste of priming fluid by inviting its injection before rather than 30 during the starting movement of the motor, so that much of the vapor of the priming is exhausted from the engine before it can be 35 compressed and exploded.

The present invention provides a separate source of fluid for priming, decarbonizing or other uses and permits the fluid to be delivered into the explosion chamber at will, 40 as during rather than before the starting movement of the motor, and when in operation for priming causes a minimum and controllable quantity of liquid to be thrown in a finely divided state into the intaken air 45 during movement of the motor, thus insuring at least one compression and ignition period with a fully-enriched charge. When in use for altering the mixture, as for providing water or kerosene for cylinder cleaning, the device provides reliable means for 50 delivering the desired quantity of fluid at the desired time; and in one form provides a conveniently controlled air inlet for diluting the explosive charge.

55 Principal objects of the invention are

hence to provide a reservoir and injection means adapted to be operated for priming or the like by an operator whose attention is engaged, as by working a starting device for the motor; to provide a device of the character 60 above mentioned which shall be effective in operation and inexpensive to manufacture and install; to provide such a device with improved means for injecting a volatile explosive priming fluid into an air intake passage of the motor in a state of fine division in order to secure relatively high saturation of the cold air in the intake passage, and thus certainly to provide an explosive mixture; and to provide for positively delivering 65 a desired charge of priming or other liquid without waste of the liquid.

I will now explain the invention in connection with species illustrating the genus defined by the claims. Referring to the accompanying drawings,

Figure 1 is a vertical section through the dash-board and the intake manifold of the engine of an automobile illustrating one form of the device;

Fig. 2 is a section on line 2—2 of Fig. 1;

Fig. 3 is an enlarged section similar to Fig. 1, illustrating a modification;

Fig. 4 is a right-hand side elevation of the device shown in Fig. 3, and

Fig. 5 is a detail plan of part of the pump.

As shown in Fig. 1 on any place convenient to the operator, for instance on the dash-board 1 of a motor car, a reservoir 2 for liquid or gas, for instance a volatile priming fluid 3 such as gasolene, rhigolene, naphtha, or an ether, is fastened by convenient means.

Preferably the reservoir 2 as shown is a 95 hollow casting having a head 4 with a projecting annular collar 5 adapted to a tight fit at one end of the preferably cylindrical bore of the reservoir 2. The collar 5 may be turned to a taper adapted to seat in a 100 tapered annular recess 6 in the reservoir 2, the parts being held assembled and held gas tight by screws 7 in holes in the heads 4 taking into tapped holes in an annular flange 8 of the reservoir 2. If desired a 105 packing gasket, paste or cement may be used to make the joint tight. Attached to, and preferably integral with and inside of the reservoir 2, a pump cylinder 10 is provided. A preferred construction is that 110

shown in which the bore of the cylinder 10 opens opposite to the opening of the reservoir 2, so that a screw plug 12 having a guide bore 13 and a flange 14 may be screwed into the threaded end of the bore of the cylinder 10, and as shown, be passed through a hole in the dash-board 1 and constitute means for supporting the reservoir 2 and its attachments on the dash-board.

10 The cylinder 10 may have an intake opening, as at 15, and a delivery port 9, and be provided with a suitable pump piston, as the mushroom-valve plunger 16 of any usual construction having a hand rod 17 passing through the bore 13 in the head 12. Rod 17 is provided with any convenient form of head for hand operation, as at 18. Preferably the plug 12 is counterbored at 19 to receive a part of the head 18, and the wall of the counterbored part is slotted at 20 to form a bayonet-clutch interlocking with projections 21 from the head 18 when the piston is forced in and turned on its axis. By this construction the pump plunger may be locked in its inmost position against pressure in the pump cylinder 10.

30 The object of the pump 10, etc., is to create an elastic fluid pressure above the liquid 3 in the tank or reservoir 2. The port 9 in cylinder 10 is provided with a spring actuated check valve 22 of the puppet type shown having its stem conveniently guided, as in a bore in a round lug 23 of the head 4, the spiral spring 24 surrounding the lug 23 and bearing on the valve 22 to hold it seated.

35 The reservoir 2 is provided with a filling spout 25 having a gas-tight closure 26 of any desired kind.

40 A suitable educt opening 27 for the reservoir 2 is controlled by a hand valve 28 of any desired construction and a pipe 29 with any usual form of connections 30 is arranged in a convenient place to conduct the fluid 3 to the intake manifold 32 of the engine. The manifold is tapped at 33 to receive a threaded plug 34 having a central opening and a nozzle 35 preferably formed as shown as a tube having one closed end and a series 50 of fine lateral perforations 36 near the closed end. Any suitable form of union 37 may hold the connection 30 and pipe 29 in communication with nozzle 35.

55 When the above described form of the device is in use, the reservoir 2 being filled to the desired extent with a volatile explosive liquid, the operator before starting will work the handle 18 for a few strokes, thus raising the comparatively small volume 60 of air or gas in the reservoir 2 to a relatively high pressure. Now upon operation of the usual starting motor and then opening the valve 28 during the necessary time, a fine spray, of an amount of priming fluid measured by the length of time valve 28 is held

open, is thrown into the intake manifold through the nozzle 35. A nozzle constructed as described is very effective to deliver a finely divided spray. A relatively high saturation of the intaken air instantly ensues, and the engine starts with ease, if the fluid 3 is a suitable fluid readily volatile into a vapor highly explosive when mixed with air. It will be understood that the conveniently placed valve 28 can be operated 70 with one hand without withdrawing attention from the starting and other controls.

In the modification shown in Figs. 3 and 4 the nozzle 35, pump 10, reservoir 2 and appurtenant devices may be the same as above mentioned, but instead of the valve 28 a three-way valve 40 having an air intake 41 and an educt passage 42 manually controlled, as by a conical valve member 43 held to its seat by a spring 45 and having a stem 46 85 is employed. A hand-operated index 44 sweeping a dial 47 is connected to the stem 46 for moving and indicating the position of the valve member 43. When in the position illustrated in Fig. 4, index 44 shows that priming fluid is being sprayed at nozzle 35.

If now the member 44 is turned to either right or left to the position marked "Stop" on dial 47, Fig. 4, the priming fluid is cut 95 off. But if the index 44 is moved down to the indication "Air" in Fig. 4 the opening 41 is connected to the pipe 29, and the suction of the engine causes a flow of air at 41. As will be understood by operators of 100 automobiles whether or not a particular fuel, adjustment of the carburetor, or conditions of temperature make priming requisite, it is often desirable to reduce the richness of the charge without altering the carburetor adjustment. The air-passage 41 and dash-board controlled valve 43 provides convenient means for doing this without disturbance of the use of the device for priming at starting.

110 It is now a familiar practice to inject into the cylinders or passages of an explosion motor ingredients not essential to the operation of the motor to alter the behavior of the exploding charge under expansion or 115 to prevent carbon deposit, or for other purposes. It has been proposed to add water, or kerosene, or emulsions of water and certain oils to the charge for one or more of these purposes. The device described is 120 readily adapted to provide a source of supply and means for the measured injection of such ingredients at the desired times, as will be apparent.

125 What I claim is:

1. A priming device for explosion motors having a source of fuel supply for the motor, a nozzle adapted to spray fluid into an intake passage of the motor, a separate closed reservoir adapted to hold a priming 130

liquid, a pump cylinder therein for creating air-pressure in the reservoir and integral with the walls of the reservoir, a pipe connection between said reservoir and nozzle, 5 and a three-way valve normally holding said pipe closed adapted upon operation either to connect said pipe to the liquid in the reservoir for priming or to connect said pipe to the atmosphere, whereby to dilute 10 the explosive charge, said nozzle having a closed end and lateral perforations.

2. A priming device for explosion motors of motor vehicles having therein a closed reservoir for priming liquid and a pump 15 cylinder within and integral with the reservoir, in combination with a closure for the pump-cylinder constituting means for attaching the reservoir and pump to the dashboard of the vehicle.

20 3. A pressure reservoir for explosion

motor priming fluid comprising therein a pump-cylinder integral with the walls of the reservoir, a port in one end of the pump-cylinder, a valve for the port, and a closure for the reservoir having thereon a guide for 25 the valve.

4. A priming device for explosion motors of motor vehicles having therein a closed reservoir for priming liquid and a pump cylinder within and integral with the 30 reservoir, in combination with a flanged closure for the pump cylinder whereby the dashboard of the vehicle is clamped between the end of the reservoir and said flange to support the reservoir on the dashboard. 35

Signed by me at Boston, Massachusetts, this 18th day of December, 1917.

WILHELM C. A. SIEVERTS.
